UNITED STATES PATENT OFFICE.

HERBERT C. LEONARD, OF ACUSHNET, AND HARRY E. WENSTROM, OF NEW BEDFORD, MASSACHUSETTS, ASSIGNORS TO GEORGE L. SPRAGUE, OF NEW BEDFORD, MASSACHUSETTS, AND WILLIAM A. REYNOLDS, OF FREETOWN, MASSACHUSETTS.

DRILL PRESS.

Application filed June 22, 1920. Serial No. 390,754.

To all whom it may concern:

Be it known that we, HERBERT C. LEONARD and HARRY E. WENSTROM, citizens of the United States, residing at Acushnet and New Bedford, respectively, in the county of Bristol and State of Massachusetts, have invented new and useful Improvements in Drill Presses, of which the following is a specification.

10 The present invention relates to drill-presses of the stationary type. The ordinary drill-press in common use is of a cumbersome construction, expensive to install and unadapted to the uses of small shops, which

15 are therefore forced to rely on the ordinary portable hand drill, which lacks the stability and accuracy necessary for certain kinds of work.

It is an object of the present invention
20 to produce a drill-press adapted to the uses of the small shop, with which the motor of a portable drill may be used as the driving means, in which the accuracy and stability of the drill-press is obtained and which has
25 a quick, accurate and positive action. Another object of the invention is to so construct the device that the weight of the motor is supported otherwise than by the drill-bit.

30 In the accompanying drawings is illustrated, one embodiment of the invention in which,—

Figure 1 is a side elevation of the drill.

Figure 2 is a section on line 2—2 of Figure 1 showing the operating lever in detail.

Figure 3 is an enlarged detail view of the suspension block.

Figure 4 shows the adaptation of the device to use with an emery-wheel.

40 Figure 5 is the adaptation of the device to a use in regrinding piston valves.

Figure 6 is an enlarged detail view of the adjusting means for the upper bracket arm.

Figure 7 is a detail view showing the sliding connection between the driving spindle and the drill spindle.

This invention will now be described in connection with the accompanying drawings, referring to the various details by reference
50 numerals, the same numerals designating the same parts in all figures of the drawings.

In a general way, the invention comprises

a cylindrical rod 10 vertically placed and secured to a suitable support 11 by means 55 of bearing members 12 and 13. Mounted on the rod 10 for vertical and angular adjustment, are bracket arms 14, 15 and 16, comprising the supporting frame for the drill, its operating mechanism and the work-table or platen. The drill proper comprises a drive spindle 17 and a drill spindle 18, which are suitably connected for rotation as a unit and to permit vertical movement of the drill spindle relative to the 65 spindle 17, as will be hereinafter set forth. The spindle 18 is supported by a lever 19, by which it may be reciprocated up and down, and the spindle 17 is suitably formed at its upper end, for connection with the 70 motor of a portable drill or other suitable driving means.

The arms 14, 15 and 16 are attached to the rod 10 by means of split collars 20, 21 and 22 respectively, which permit adjustment of the bracket arms longitudinally and rotatively in relation to the rod 10. The collars are provided with outstanding flanges 23 and 24 receiving clamping bolts 25 by which they may be drawn up to grip 80 the rod and hold the arms in adjusted position.

The bracket arm 15 is provided with an upper branch 26 and a lower branch 27, on the respective outer ends of which are 85 sleeves 28 and 29. Spindle 17 is rotatably supported in the sleeve 28 and sleeve 29 acts as a guide for spindle 18. The spindle 17 is provided near its upper end with an outstanding flange 30, by means of which it is 90 supported upon the sleeve 28 through intermediate ball-bearings 31, the bearing consisting of race-ways 32 and 33 between which the balls are confined. The upper end of the spindle 17 may be squared as at 34 or 95 otherwise suitably shaped to adapt it to fit into a socket in the motor drive shaft.

The drill spindle 18 is provided with a longitudinal bore opening at its upper end, into which the downwardly extending 100 spindle 17 is telescoped. The spindle 17 is provided with a longitudinal groove 35 in which a pin 36 projecting from the inner surface of the bore of spindle 18 is adapted to slide, preventing relative rotary movement of the spindles while permitting re-

- ciprocation of the drill spindle. On the lower end of the drill spindle is a chuck 37 in which a suitable drill 38 or other tool may be carried.
- 5 The lever 19 by which the drill spindle 18 is supported is pivotally attached at one end to the branch arm 26 by a bolt 39 or other suitable means and is held normally in its raised position by means of springs 10 40, which are preferably two in number and are secured at one end to a pin 41 extending transversely through a projection 42 on arm 26 and at their other end to a similar pin 43 extending transversely through the 15 lever arm. The lever is depressed against the force of these springs in carrying out the drilling operation and is automatically returned to its upper position by the springs when released by the operator.
- 20 On the outer end of the lever 19 is a hand-grip 44 by which the lever may be depressed, and intermediate of the lever ends is a yoke having parallel side members 45, having slots 46. Within the yoke and between the 25 side members 45 is pivoted a centrally apertured suspension block 47 suspended by means of pins 48 which extend into slots 46. The spindle 18 is supported in the aperture of the block 47 by means of an outer standing flange 49 formed on the spindle and resting on the upper face of the block. By this arrangement of the suspension block sufficient play between the block 47 and lever 19 is provided to prevent binding of the 30 spindles in their guide sleeves when the lever is oscillated.
- 35 On the outer end of the bracket arm 16 is a split sleeve 50, in which is mounted for vertical adjustment, a stem 51 which is attached to the lower face of a platen 52. Any suitable driving means may be used in connection with the drill as an electric motor, a compressed-air motor or the like. In Figure 1 of the drawings, the driving means 40 for the drill-bit shown is an electric motor 53 of a portable hand-drill, which is shown as having the end of its rotor socketed to receive the squared end 34 of the spindle 17. The rotor is thus in alinement with the 45 spindle 17.
- 50 The weight of the motor 53 is supported by the branch arm 26 which relieves the drill-bit of too great pressure when the drill-bit comes in contact with the work and the operator of the necessity of supporting the motor.
- 55 By mounting the motor in this manner, the tendency to break drill-bits resulting from allowing the weight of the motor to 60 rest on the drill is minimized. The motor is held on the end 34 of the spindle 17 by means of bracket 14, which is provided with a split sleeve 54 on its outer end having a suitable adjusting nut 55 for clamping the 65 handle or other projection of the motor.
- To accommodate the bracket 14 to motors of different sizes and types, it is made in two sections 56 and 57, slidably arranged one relative to the other in a horizontal direction the sections being secured together 70 by a bolt 58 extending through an aperture in one of the members and slideable in a slot 59 longitudinally arranged in the other member. Both the platen and the arm 16 are adjustable to bring the work into proper 75 position relative to the drill and the arm may be swung aside when desirable and the article to be drilled placed on the floor or other support as in the case of drilling holes in the ends of rods or other like objects. 80 The platen may also be removed from the sleeve 50 altogether and replaced by a suitable center 60 (see Figures 4 and 5) and a grinding tool as an emery-wheel 61 may be mounted between the center 60 and the 85 chuck 37, or a piston valve 62 may be mounted therebetween (see Figure 5,) for regrinding when worn. The sleeve 29 is split and provided with flanges 63 and 64 through which passes an adjusting or clamping bolt 90 65. The lever arm 19 may be clamped in fixed position by means of a clamping nut 66 screwthreaded on to the end of the bolt 39.
- When the drill spindle is operated, the 95 suspension block 47 has a tendency to turn within the yoke in a plane at right angles to the axis of the spindle 18, with a consequent binding of the block 47 between the side members 45. Turning of the block in 100 a plane at right angles to the axis of the spindle 18 may be prevented by properly machining and truing the block to snugly fit the inner faces of the side members 45. This however is an expensive and time consuming operation. To overcome these objections in an inexpensive manner the block 105 47 is provided with a projecting tongue 47^a which extends into and is adapted to ride in a slot 19^a formed in the lever arm and communicating with the opening in the yoke. By this construction oscillation of the block 47 on pins 48 is permitted while turning of the block in a plane at right angles to the axis of the spindle is prevented. 110
- 115 In the machine, as set forth above, a drill-press is provided having a quick positive action, which is cheap and simple of construction and which provides for a direct drive between the driving spindle and the 120 motor; eliminating all gears, belts and like mechanism, likely to get out of order and expensive of replacement. By means of this device the portable hand-drill is adapted to the uses of a drill-press securing all the advantages of a mechanically guided tool. The adaptability of the machine to many uses and its simple, cheap construction adapt it to the needs of a small shop.
- 125 Having thus explained the nature of our 130

said invention and described a way of making and using the same, although without attempting to set forth all of the forms in which it may be made or all of the modes of 5 its use, what we claim is:—

1. In a drill, a supporting frame therefor, a two-part spindle, comprising a drive spindle and a drill spindle telescopically arranged one in the other, said drive spindle 10 being mounted to rotate without longitudinal reciprocation, inter-engaging means between said spindles whereby said drill spindle is rotated by said drive spindle and at the same time is free to reciprocate longitudinally thereof, a drill on the end of said drill spindle, a lever pivoted at one end to the frame for reciprocating the drill spindle, said drill spindle being pivotally attached to said lever and means alined with and attached to the end of the drive spindle for rotating the same.

2. In a drill, supporting means therefor, a two-part spindle comprising a drive spindle and a drill spindle, telescopically arranged 25 one to the other, said drive spindle being mounted to rotate, inter-engaging means comprising a lug on one of said members and a longitudinal groove in the other into which said lug projects whereby said drill spindle is 30 rotated by said drive spindle and at the same time is free to be reciprocated longitudinally thereof, a drill on the end of said drill spindle, a lever mounted on the frame by which the drill spindle may be reciprocated and a motor attached to the end of the drive spindle for rotating the same by a direct drive.

3. A drill, supporting means therefor, a two-part spindle comprising a drive spindle 40 and a drill spindle telescopically arranged one to the other, said drive spindle being mounted to rotate, inter-engaging means between said spindles whereby said drill spindle is rotated by said drive spindle and at the same time is free to reciprocate longitudinally thereof, a drill on the end of said drill spindle, means to reciprocate said drill spindle and means attached directly to the drive spindle for rotating the same, a motor 45 mounted on the upper end of said drive spindle, and adjustable means for holding a motor on the upper end of said drive spindle.

4. A drill, having a main supporting rod, arms extending from said rod, sleeves on 55 the ends of the arms, a drive spindle and a drill spindle mounted in certain of said sleeves and in telescopic relation one to the other, said drive spindle being mounted for rotation and said drill spindle being mounted for rotary and reciprocal movement, inter-engaging means between said spindles whereby the drill spindle is rotated by said drive spindle and is at the same time free to reciprocate relative thereto, a motor having 60 its drive shaft in alinement with and

coupled to said drive spindle, and a lever arm for reciprocating said drill spindle.

5. A drill, comprising a vertical rod having a horizontally extending arm adjustably mounted thereon, a sleeve on the outer end 70 of said arm, a lever pivoted to said arm, having a loop intermediate of its ends, a suspension block pivotally and slidably mounted in said loop, a drive spindle rotatably mounted in said sleeve, a drill spindle having a drill on its lower end mounted in said suspension block, and adapted to be reciprocated by said lever, said drill spindle having a bore extending longitudinally thereof from its upper end into which the drive spindle extends, one of said spindles being provided with a longitudinal groove, a lug on the other spindle projecting into said groove, and a driving motor connected directly to said driving spindle and means for securing 85 said motor on said driving spindle.

6. A drill, comprising a vertical rod having a horizontally extending arm adjustably mounted thereon, said arm being provided with an upper and lower branch, sleeves on 90 the outer ends of said branches, a drive spindle rotatably supported in the sleeve of the upper branch, a drill spindle slidably and rotatably mounted in the sleeve of said lower branch, said spindles being telescopically arranged relative to each other, one of said spindles having a groove formed therein, a lug on the other of said spindles fitting into said groove, a lever pivoted at one end to said arm, a loop intermediate the ends of 100 said lever, having parallel side members, slots therein extending longitudinally of said side members, a suspension block having lugs extending therefrom and into said slots, said drill spindle being supported by 105 said suspension block and adapted to be reciprocated by said lever, a motor attached to the upper end of said drive spindle, and an adjustable arm extending from said vertical rod having clamping means thereon for 110 clamping the motor in position on said drive spindle.

7. A drilling apparatus comprising a motor having a driving spindle, a drill spindle, a platen, an upright, brackets on said upright adjustable about a common axis and adapted to receive said motor, drill spindle and platen respectively, means for connecting said drive spindle and said drill spindle, and means for axially reciprocating 115 said drill spindle toward and from said platen while said motor is held stationary.

8. A drilling apparatus comprising a motor, a platen, an alined drive and a drill-spindle therebetween, an upright, brackets 120 for supporting said motor, spindles and platen, extending from said upright, and mounted thereon for pivotal and longitudinal adjustment independently of each other, means for connecting said drive and drill 130

- 4
- spindle, and means for reciprocating said drill spindle axially toward and from said platen.
9. A drill apparatus, comprising an upright, upper, lower and intermediate bracket arms extending from said upright and adjustable thereon independently of each other, a motor held between the upper and intermediate arms and a drive spindle connected thereto, a drill spindle rotatably connected to said drive spindle and a lever on said intermediate arm for axially reciprocating said drill spindle independently of said drive spindle.
10. A drilling apparatus comprising an upright, bracket arms extending therefrom, a motor fixedly mounted on certain of said brackets, a platen therebeneath fixedly mounted on a bracket arm, a drive spindle on said motor, a drill spindle rotatably connected and in alinement therewith intermediate of said motor and said platen, and means for reciprocating said drill spindle.
11. A drilling apparatus, comprising an upright end bracket arms extending therefrom, an intermediate bracket arm having an upper and lower branches, sleeves on the ends of said branches, a drive spindle rotatably supported in the sleeve of said upper branch, a drill spindle connected with said drive spindle and slidably mounted in the sleeve of said lower branch, and a pivoted lever arm engaging the drill spindle intermediate of said branches for reciprocating said drill spindle.
12. A drilling apparatus comprising an upright, a motor and a drive spindle connected therewith, a drill spindle connected in alinement with said drive spindle, a bracket arm adjustable rotatably about said upright, and a platen rotatably adjustable on the end of said bracket arm.
13. A drilling apparatus comprising an upright cylindrical bar, means for supporting said bar, a motor supported for rotary adjustment about said bar, a chuck supported for rotary adjustment with said motor and movable axially relative thereto, a platen supported by said bar below said motor and adjustable both longitudinally of said bar and rotatable about the axis thereof, and means for moving said chuck relative to said motor toward and from said platen.
14. A drilling apparatus comprising an upright, a motor and platen secured thereto, a bracket arm extending from said upright and adjustable thereon, said arm comprising an upper and a lower branch, sleeves at the outer end of said branches, a drive spindle mounted for rotation in the upper sleeve and a drill spindle mounted for rotation and axial reciprocation in said lower branch, the drive spindle being connected to said drill spindle and to said motor and means mounted on said bracket for reciprocating said drill spindle.
15. A drilling apparatus comprising a supporting structure, a drive spindle and a drill spindle mounted thereon, motive means for said spindles, a lever pivoted to said support and adapted to axially reciprocate said drill spindle, said lever being provided with a yoke having slotted side members, a suspension block suspended within said yoke and having pins extending into the slots of the side members, the lever being provided with a slot, and a projection on said block extending into the slot in the lever whereby movement of the suspension block at right angles to the axis of the spindle is prevented.
16. A drilling apparatus comprising a motor having a rotor, a drive spindle in alinement with said rotor and connected thereto to be driven thereby, a driven spindle in alinement with said drive spindle and movable axially thereof, and work-holding means operatively related to said driven spindle.
17. A drilling apparatus comprising a motor having a rotor, a drive spindle in alinement with said rotor and connected thereto to be driven thereby, a driven spindle in alinement with said drive spindle and movable axially thereof, and means for attaching a tool to said driven spindle.
18. A drilling apparatus comprising an upright cylindrical bar, brackets at the opposite ends of said bar for attachment to a post or wall, a motor supported by said bar rotatably adjustable thereabout and having the axis of its rotor parallel with said bar, a platen supported by said bar below the motor and adjustable both longitudinally of said bar and rotatably about the axis thereof, a tool-holding chuck connected to said rotor and adjustable therewith for operation thereby and having its axis parallel with the axis of said bar, and means by which the said chuck may be moved towards and from the platen.
- In testimony whereof we have affixed our signatures.
- HERBERT C. LEONARD.
